UNITED STATES PATENT OFFICE

1,984,750

APPARATUS FOR HANDLING RODS

Frank W. Lorig, Lakewood, Ohio

Application December 31, 1931, Serial No. 584,270

1 Claim. (Cl. 242—79)

This invention relates to a method and apparatus for handling rods delivered by a rolling mill, one of the inventor's objects being to facilitate the loading of rod bundles on an endless conveyor.

5 Continuous rod mills require a minimum of two rod coiling reels per strand of rods delivered from the mill, that is, two reels are necessary for a single strand and four for a double strand rod mill.

10 These reels have heretofore been arranged with conveyers in two general schemes. One is to place the reels in a row parallel to and alongside one conveyer, and the other is to use a plurality of conveyers with an individual reel placed 15 at the end of each conveyer.

15 The conveyers used with rod reels are of two general types. One uses chains with dogs projecting above stationary apron plates over which 20 the rod bundles are dragged. The other has a movable apron. The chain and dog types of conveyers are further divided into two types, those having a single chain where the rod coils are placed over the dogs and the coil is pulled, and those having a double chain with dogs which 25 push the coil. Conveyers with dogs can pull a bundle of any size rod, but cannot push bundles of fine gage rods satisfactorily, because the coils in frictional contact with the conveyer apron or 30 table bend backward.

30 To overcome this distortion of the lower coils of a rod bundle on conveyers of the chain and dog type, single chain conveyers are used with continuous mills rolling fine gage rods. On the 35 majority of these mills, especially those equipped with the pouring type reels, manual removal of the bundles from the reels is practiced. This method of handling bundles collapses them from the form made by the reels. A collapsed bundle 40 is so placed on the conveyer that one of the dogs of a continually running chain enters within the coils and drags it forward. The conveyer in this case is never fully loaded.

45 It is impractical to manually remove from the reels the heavy and high coils being made by modern rod mills. It is also desirable that the bundles retain the form given them by the reels, as it reduces the time necessary for cooling. Therefore, modern pouring reels are equipped 50 with power pushers which remove the bundles in the desired form. But to place a rod bundle over a dog on a single chain conveyer by means of a pusher requires the use of additional intricate mechanism at each reel, or placing a reel at the loading end of a conveyer, so that the pusher

places the bundle over the place on the conveyer where the dog will enter within the coils of the bundle as it rises above the surface of the conveyer plate or apron. To obtain this latter arrangement a plurality of conveyers with one reel at the end of each conveyer has been used. Also, to obtain the minimum length of conveyers for the required cooling time they are operated intermittently, moving the distance between dogs every time a bundle is pushed on the conveyer.

5 10 The use of a conveyer for each reel has the following objections: No spare reels, which are very desirable, can be installed without its conveyer; the increased installation cost, because of the number of drives and tail sprockets required; and the bundles are discharged from the conveyers at as many places as there are conveyers requiring expensive collecting equipment or excessive labor.

15 For the use on mills rolling rods of a heavy 20 gage, pouring reels with power pushers have been installed in a row alongside an intermittently operated conveyer having a double chain with dogs spaced at a distance equal to that of the reel centers. The dogs when at rest are between 25 reel centers so that the bundle can be placed on the conveyer between the dogs. As each bundle is deposited on the conveyer from its respective reel the dogs move one space forward pushing the bundles ahead of them. In order to have a 30 fully loaded conveyer to obtain maximum cooling, the reels must be operated in a certain prescribed sequence to prevent a bundle being in a space into which it is desired to push another coil from the reel. This sequence of reel operation is often times difficult to obtain, as numerous delays and other occurrences at many places in the mill will interrupt it, causing irregular and interrupted operation of the conveyer with the consequent difficulties in handling the bundles at the discharge end of the conveyer.

35 All of the above mentioned undesirable conditions have been overcome by the present invention. The principal feature of this invention is the grouping of a plurality of reels about the 45 loading end of a conveyer in such manner as to permit the coiled bundles of rods to be power pushed from all reels to a single point on the conveyer table, which in a dog and chain conveyer is the point at which the dog rises above 50 the conveyer table or apron and enters inside the coiled bundle. The conveyer is operated intermittently to move forward the distance of the chain dog spacing as each rod bundle is pushed from its respective reel to this single loading 55

point on the conveyer table. These arrangements can also be used with intermittently moving apron conveyers. The conveyer, either type, being always fully loaded, provides maximum cooling of the bundles.

Referring to the accompanying drawings:

Figure 1 is a top plan illustrating the method and one form of the apparatus incorporated in the invention.

10 Figures 2, 3 and 4 are top plans of suggestive modifications.

Figure 5 is a cross-section on the line V—V of Figure 1.

In detail, rods are led from the last stand of 15 rolls 1 of a continuous multi-strand rod mill, through swinging conduits 2 of switching mechanisms 3 and selectively through rod delivering conduits 4 having interposed cooling water receiving boxes 5, this, so far, being a conventional 20 arrangement. These rods are loaded on pouring reels 6 at the ends of the delivering conduits 4, these reels being grouped radially about a point X at the receiving ends of endless drag conveyers 7. These pouring reels 6 are each arranged with 25 a stripping plate 8 and a push-off ram 9, the latter being arranged to push bundles from this plate to the receiving end of the conveyer. This last arrangement and its operation are disclosed in the patent to B. N. Bletso et al., numbered 30 1,850,492, entitled "Rod reeling mechanism" and filed August 3, 1931.

The conveyers 7 are of the usual intermittently operated type which are provided with dogs adapted to be engaged within the coils or bundles of rods as they are deposited on the conveyer.

Reference may be made to the patent to G. H. Rose, numbered 1,865,337, entitled "Conveyer" and filed November 21, 1931, for a disclosure of 40 the above.

It is to be noted that the invention is primarily applicable to mills using the modern type of equipment, that is, reels having stripper plates which raise the formed coils and pushers which then horizontally discharge these coils from 45 these stripper plates to a conveyer or conveyers, and conveyers having surface plates and dogs which rise at a common point thereabove and drag or push the coils thereover. The patents referred to are representative of such equipment.

The reels 6 may be grouped about the receiving

ends of the conveyers 7 in various numbers, the minimum permissible being two for each strand of rod, because one must be stopped and the rod bundle formed thereon loaded on a conveyer while another is receiving the continuously delivered rod. The various figures of the drawings suggest different arrangements.

The method of using the apparatus illustrated is substantially as follows: The rods delivered from the rolls 1 are switched, in each instance, 10 to an empty one of the reels 6 by means of the switching mechanisms 3. When these are filled the rods are switched to other empty reels and the stripping plates 8 of these loaded reels are raised so that the push-off rams 9 can shove the 15 rod bundles from these reels onto the point X of the conveyers, the latter being then operated to move a distance equal to the space between the conveyer dogs so as to drag each bundle clear and permit the rod bundles now forming on the 20 other reels to be subsequently loaded in a similar manner. If three or more reels are provided for each strand a spare reel will always be ready for emergency use, which is desirable in case one of the two necessary reels should be rendered inoperative. If desired, the rod bundles may be manually moved from the reels 6 to the receiving 25 ends of the conveyers 7, in which case a more simplified form of reel arrangement may be used.

The arrangements shown in Figures 3 and 4 30 may be used for a two strand mill, thus eliminating the need of a second conveyer.

While a specific form of the invention has been shown and described in accordance with the patent 35 statutes, it is to be understood that it is not desired to limit the invention exactly thereto, except as defined in the appended claim.

I claim:

A rod-mill layout including a rod-bundle conveyer and a plurality of rod reels of the type having push-off members, said reels being grouped adjacent the receiving end of said conveyer in such arrangement that said push-off members are radially disposed respecting the loading point 40 of the same and so that rod-bundles formed by any one of said reels may be pushed towards the loading point of said conveyer and the latter operated regardless of the sequence with which 45 said reels are operated.

FRANK W. LORIG.
